Patented Oct. 23, 1917.

UNITED STATES PATENT OFFICE.

MILTON D. STOCKING, OF LINDENWOOD, ILLINOIS.

FEED-TROUGH.

1,244,256.

Specification of Letters Patent. Patented Oct. 23, 1917.

Application filed June 28, 1915. Serial No. 36,754.

To all whom it may concern:

Be it known that I, MILTON D. STOCKING, a citizen of the United States, residing at Lindenwood, in the county of Ogle and State of Illinois, have invented certain new and useful Improvements in Feed Troughs, of which the following is a specification.

This invention relates to feed troughs adapted for feeding stock and especially 10 hogs, and embodies improvements in feed troughs such as disclosed in Patent No. 1,126,907, granted to me February 2, 1915.

One of the primary objects of my present invention is to so improve the construction 15 of troughs of the type shown in my prior patent that they will be better adapted for service.

Another object of my invention is to provide means for dividing lengthwise the open 20 top of the trough and serving as a partition for preventing hogs on one side of the trough from interfering with those on the other side and from stepping into the trough.

A further object of my invention is to 25 improve the construction of the trough supporting means and of the means for clamping the trough thereto whereby the latter means may be more freely and easily operated when removing the trough.

30 My invention, its mode and principle of operation will become better understood by reference to the following description when considered in connection with the accompanying drawings, wherein;

35 Figure 1 is a plan view of a feed trough embodying my improvements;

Fig. 2 is also a plan view of my improved feed trough but showing it converted into a water trough;

40 Fig. 3 is an enlarged transverse sectional view taken on the line 3—3 of Fig. 1; and

Fig. 4 is a fragmentary front elevation of the left hand portion of the trough shown in Fig. 1.

45 The trough designated in general by reference character 5 may be suitably constructed to form a rectangular open-top receptacle the sides and ends of which taper inwardly, as clearly shown in the drawings, the trough being provided at its top with a horizontal rim 6 having a depending flange 7. Means are provided for so supporting the trough that the same may be removed at will, when it is desired to clean the trough or, as is necessary in winter, to remove ice from the trough, this being easily effected by invert-

ing the trough and lightly rapping the same to loosen the ice.

The immediate means for supporting the trough comprise a plurality of brackets, each 60 formed of a strap iron strip designated in general by reference character 8, shaped at its central portion to form a seat to conform to and receive the bottom and sides of the trough, as clearly shown in Fig. 3, 65 and then bent downwardly and inwardly forming braces or leg standards 9 and thence inwardly and upwardly in juxtaposition to the depressed central portion of the strap-iron and being fixedly secured to said central 70 portion. Sills 11 to which the brackets are secured by suitable means serve as a base for the trough and are held in fixed spaced relation by a stringer 12, interposed between the sills and the raised central portion of the 75 brackets and fixedly secured to each sill. From the foregoing, it will be apparent that the said trough may be removed at any time from the supporting means and that the latter, being simple in construction, is such that 80 only the ends of the strap-iron members 8 and sills 11 project beyond the trough, and thus there is very little trough supporting structure subject to being trampled on or interfered with by hogs while feeding. 85

The trough is secured to its supporting means in such manner as to be easily removed therefrom at any time. The means for so holding the trough in connection with the supporting means comprise a U-shaped 90 clamping member 10 for each strap-iron support, the arms of said member being yieldable and formed with reduced ends 13 turned inwardly. Portions of the outer sections of the strap-iron supports are punched inwardly forming apertures 14 and ledges 15. The apertures and the arms of the U-shaped clamping members are so arranged that when said members have been placed transversely across the trough above the strap-iron supporting means, the ends of the said clamping members will engage the outer sides of said supporting members, and by forcing the former downwardly the ends thereof will yield until the apertures 14 are 105 reached when said ends will spring into the apertures, thereby locking the trough against being removed. Cotter pins 16 passed through the ends 13 of each clamping member at the inner side of the supports, lock 110 the clamping means against being removed accidentally. To remove the trough, any one

end of each clamping member may be pried outwardly and disengaged from its supporting member and then swung upwardly upon its opposite end as a fulcrum, it being apparent that such movement may be easily effected by reason of the fact that said opposite ends rest on the ledges 15 and are precluded from displacement by the cotter pins 16 and shoulders 17.

10 In addition to removably securing the trough to the supporting means the members 10 perform the further function of supporting a means for dividing the trough lengthwise so as to prevent hogs from crossing the trough or from interfering with those on the other side. This means comprises a division-board 18 extending substantially in the length of the trough and secured in upright position intermediate the sides thereof to the members 10 by means of angle-bars 19. This division-board does not project downwardly into the trough compartment and its purpose is mainly to prevent hogs from climbing into the trough and to prevent hogs on one side of the trough from interfering with those on the other, thus serving, when a large number of hogs are feeding, a very useful purpose in keeping the hogs evenly distributed about the trough.

15 20 25 30 35 40 45 50

When it is desired to use the trough for watering purposes only, the division-board 18 may be removed and the top of the trough intermediate the end supports may be covered by suitable means so as to prevent access to the central portion of the trough. Such means are provided in a very simple manner by mounting a board 21 on the top of the trough, as shown in Fig. 2, and securing an extension 22 to the underside of each end of the board adapted to project beneath the end clamping members and thus prevent the board 21 from being displaced. It will thus be apparent that only the end portions of the trough are open so that there is no possibility of hogs or other stock trampling in the trough and polluting the water; and with this means it is not necessary to refill the trough as often as in cases where the trough is entirely open or is of comparatively small capacity.

It will be obvious that the trough may be made any suitable length and an appropriate number of strap-iron supports and blocks

provided, and that when three or more supporting means are utilized, the covering means or board 21 may be sprung or flexed upwardly at its center to pass over the centrally disposed clamping members.

The base of the present support, made up of the sills 11 and the stringer 12, has important advantages over the base shown in my prior Patent No. 1,126,907, as follows: One stringer 12 is disposed at the middles of the sills 11, whereby there are no obstructions along the ground at opposite sides of the trough. Furthermore, the weight of the trough is supported more directly by the base for the reason that the trough supporting brackets rest at their middles directly on the base.

70 I claim:

1. A feed trough support comprising transverse supports extending beyond each side of a trough and provided thereat with openings, and U-shaped clamping members 75 the ends of which are reduced so as to form shoulders at the neck of the reduced portions, the reduced ends being turned inwardly and adapted to locate in said openings when the clamping members have been 80 positioned across the top of a trough to secure the same to the supports, the shoulders at either end of the clamping members being adapted to abut against the outer sides of the supports when the opposite ends of 85 the clamping members have been disengaged from the supports and raised to permit removal of a trough therefrom.

2. A support for feed troughs comprising a pair of sills, a stringer connecting the sills 90 at the middles and across the tops thereof, and a trough-supporting bracket for each sill, said bracket consisting of a metal strap bent at an intermediate portion to form a seat for the reception of a trough, and also 95 bent to form leg standards depending from opposite ends of the seat and resting upon the end portions of a sill, the opposite end portions of the strap extending inwardly from the leg standards and overlapped beneath and secured to the bottom of the seat portion and constituting a tie bar for the leg standards, the intermediate portion of the tie bar being elevated to span the stringer.

100 MILTON D. STOCKING.
